UNITED STATES PATENT OFFICE.

W. B. McCLURE, OF ALEXANDRIA, VIRGINIA.

IMPROVEMENT IN CART-SADDLES.

Specification forming part of Letters Patent No. 97,789, dated December 14, 1869.

To all whom it may concern:

Be it known that I, W. B. McCLURE, of Alexandria, in the county of Alexandria and State of Virginia, have invented a new and useful Improvement in Cart-Saddles No. 2; and I do hereby declare that the following is a full and exact description of the same, reference being had to the accompanying drawings, and to the letters of reference marked thereon.

This invention relates to that class of cart-saddles which employs certain devices for permitting the chain to move from side to side in the groove of the saddle as the position of the shafts is changed; and it consists, mainly, in the employment of rollers in the groove, which have their bearing in semicircular depressions, as will be fully described hereinafter.

In the drawings, Figure 1 represents a perspective view, and Fig. 2 a central sectional elevation.

To enable others skilled in the art to make and use my invention, I will now proceed to describe its construction and operation.

A represents a cart-saddle of the ordinary form, which is provided with the usual groove, *a*.

b b represent rollers, which are located in the semicircular depression *a'* of the saddle, and secured from displacement by means of the bolts *c*, which pass through the orifices of the rollers, as shown. The rollers do not rest upon the bolts, as is usually the case, their orifices being greater in diameter than their bolts, but have their bearing in the depressions *a'*. To obviate the excessive friction that would necessarily occur if the rollers rested directly upon the wood of the saddle, I provide curved bearing-plates *a²*, which are secured in the depressions in any suitable manner.

The advantages of the construction shown are as follows: As the weight of the load rests upon the rollers, and as the rollers bear directly upon the saddle, there is no possibility of any part being broken or bent by the strain. If the rollers be supported by the bolts, as has been done, the latter are liable to be soon bent out of place by the load, and then become worse than useless. The bolts also serve to bind the sides of the saddle together and prevent it from splitting—a result that frequently occurs in the ordinary saddle.

The operation of my invention will be easily understood. As the position of the shafts changes on account of irregularities of the ground, the back-chain freely adjusts itself upon the saddle, and thus relieves the animal from the excessive strain ordinarily received under such circumstances.

My improvement can be easily applied to saddles in use, as well as new saddles, at a very small cost.

Having thus fully described my invention, what I claim as new, and desire to secure by Letters Patent, is—

1. The employment of rollers in the groove of a cart-saddle, when said rollers have their bearing directly upon the saddle, substantially as described.

2. The cart-saddle described, having the groove *a*, depression *a'*, rollers *b*, bearing-plate *a²*, and bolts *c*, when combined and arranged as described, for the purpose set forth.

W. B. McCLURE.
